Wm. Wallace White

UNITED STATES PATENT OFFICE.

THOMAS CLARENCE O'MARA, OF DALGETY, NEW SOUTH WALES, AUSTRALIA.

PUMPING APPARATUS.

1,353,845.

Specification of Letters Patent. Patented Sept. 28, 1920.

Application filed March 17, 1920. Serial No. 366,605.

To all whom it may concern:

Be it known that I, THOMAS CLARENCE O'MARA, a subject of the King of Great Britain and Ireland, residing at Dalgety, in the State of New South Wales, Commonwealth of Australia, have invented certain new and useful Improvements in Pumping Apparatus; and I do hereby declare the following to be a full, clear, and exact description of the invention, such as will enable others skilled in the art to which it appertains to make and use the same.

My invention relates to improvements in pumps in which water or other liquid will be raised by employing the momentum of a fluid such as compressed air the supply of which is controlled by suitable valve devices.

I prefer to use my improved pump in deep wells, and for raising water containing sand and gravel, but it has other applications. The desirability of my construction is due to the absence of parts likely to get out of order, and to the simplicity of its mechanism.

In the drawing herewith an elevation, partly in vertical section is shown of construction embodying my invention. I do not show any valve device used to control admission and exhaust of the impelling fluid, such as compressed air, as there are well known forms of 4-way valves which are usable.

The drawings are diagrammatic, as in practice the proportions, designs, and respective positions of various parts may differ from those illustrated.

I provide as compressed air inlet means, a pair of pipes 3, 4 each having a branch 3^a, 4^a to act as an exhaust pipe. These four pipes are controlled by a 4-way rotary or other suitable valve, not shown but known as aforesaid, which will be operated by any convenient means so as to at one time open pipes 3 and 4^a, and close pipes 3^a and 4.

Alternately the valve will close pipes 3 and 4^a and open pipes 3^a and 4.

In pipe 3 is a float ball 1 and in pipe 4 a float ball 2. These balls have respective seats 12, 12^a above them, and respective gratings 13, 13^a below them.

The gratings 13, 13^a prevent the balls dropping into the pump barrels next mentioned and when any ball is raised to its seat it prevents outward passage of water past it.

I provide two pump barrels, 5, 6 and con-

nect to them the pipes 3, 4 respectively at suitable distances below the heads of the barrels. The latter are united at their heads and at their bases.

At their upper ends they are joined to the base of a water receiving chamber 11, which will receive water from each barrel 5, 6, alternately when the pump is at work. Chamber 11 contains a rocking lever 18 which at each end carries a connection or rod 18^a, 18^b, respectively, each carrying a float valve 19, 20, respectively. The lever 18 is caused to alternately raise and lower its valves, thus closing and opening the seats 19^a, 20^a through which rods 18^a, 18^b extend, and which are provided to allow passage of water from barrels 5 and 6 into chamber 11 which has any suitable delivery, as pipe 21.

The barrels 5, 6 are at their bases united by tubing 7 of U form. The limbs of the U tubing, or the bases of barrels 5, 6 are provided with valve seats 8, 9. The U tubing contains a ball valve 10, which when the pump is operating will be moved by water up one or other limb of the U tubing, water being then forced down barrel 5 or 6 as the case may be. This ball valve will thus close seat 8 or 9.

The pump barrels 5, 6 have branch feed pipes 14, 15 which have their tops located so as to admit water into barrels 5, 6 above the valve seats 8 and 9.

Each branch pipe 14, 15 extends downward for any suitable distance to enter the water to be raised and is fitted at or above its base with a seat, a grating and a ball or foot valve each ball or foot valve falling automatically to close its seat except when raised as explained hereinafter. The respective seats are marked 16, 17, the gratings 16^a, 17^a, and the ball or foot valves 16^b, 17^b.

To operate this pump its lower part is immersed in water, which may, but need not, reach to level A. For starting purposes the barrels 5 and 6 are then supplied with water (through delivery pipe 21 for example) so as to fill the said barrels and the connected pipes 3 and 4 to a suitable height—as to seats 12, 12^a of float valves 1, 2.

The aforesaid rotary or other control valve device (not shown) is then operated, and the air under pressure is admitted, through for example pipe 3, the outlet 4^a being kept at this time open. The said compressed air flows forward and presses the

water in pipe 3 into barrel 5, some of the water in which is accordingly forced upward, and other water therein is forced downward. The water forced upward 5 closes valve 19 on its seat and moves the rod 18^a and the lever 18 and accordingly moves rod 18^b and opens valve 20.

The water forced as stated down barrel 5 forces ball 10 before it so that that ball rises 10 to and closes seat 9 in barrel 6; but during the said ball movement it forces water in barrel 6 to move upward.

Since valve 9 has been suddenly closed by ball 10, a suction is caused at and about 9— 15 by the water flowing up barrel 6—thus water is drawn into 6 through pipe 15, past valve 17^b which is lifted by the suction. The water thus raised in barrel 6 passes the seat 20^a and enters the chamber 11 until the 20 conclusion of the impetus of water up barrel 6 whereupon valve 17^b closes on seat 17 and suction up pipe 15 ceases. When water is thus pumped up barrel 6 the water fills pipe 4 up to the float valve seat 12^a. During the 25 actions just explained any air in pipe 4 becomes discharged through the pipe 4^a.

The next action of the said rotary or other valve device closes the pipes 3, 4^a, and opens the alternate set of pipes 3^a and 4, 30 and admits air under pressure into pipe 4, while the compressed air in pipe 3 becomes discharged through pipe 3^a.

The air thus admitted to pipe 4 forces the water in that pipe into barrel 6, and (in 35 the manner described as to barrel 5) thus closes valve 20, and opens valve 19. The pressure of water downward in barrel 6 carries ball 10 (in the manner described as to barrel 5) up to close seat 8 in barrel 5. 40 This action accordingly drives water up barrel 5 and produces suction up branch tube 14, when ball 10 closes seat 8 so that water is drawn through pipe 14, lifting ball valve 16^b, and entering barrel 5. Water 45 from barrel 5 is thus delivered into chamber 11 as will be obvious.

When water is pumped up barrel 5 as last explained the water fills pipe 3 to the float valve seat 12.

One series of pumping movements is thus 50 completed and the pump further operates repeating the series, the pipes 3, 4^a being again opened, and pipes 3^a, 4 being closed.

Having described this invention, what is claimed is:

1. In a pumping apparatus, the combination of a water chamber having an outlet, a pair of barrels each communicating at one end with said chamber, said barrels being in communication with each other at their opposite ends, each of said barrels having an inlet, means for supplying fluid under pressure to said barrels, valves for controlling the communication between the barrels and said chamber, valves for controlling the inlet to said barrels, and a valve for controlling the communication between the barrels, all of said valves being adapted for operation alternately in opposite directions.

2. In a pumping apparatus, the combination of a receiving chamber having an outlet, a pair of barrels each provided with a valve-controlled opening at one end in communication with said chamber, a rocking lever in said chamber and provided with 75 valves for controlling said openings, each of said barrels being provided at its opposite end with a valve seat, a tube connecting said valve seats, a valve in said tube adapted to alternately close said seats, a pair of valve-controlled liquid supply pipes in communication with said barrels, and a pair of valve-controlled supply pipes for fluid under pressure also in communication with said barrels, each of said tubes having an exhaust 80 opening, all of said valves being adapted for alternate operation to supply fluid under pressure and liquid to one of said barrels.

In witness whereof I have hereunto set my hand.

THOMAS CLARENCE O'MARA.
